Primary Examiner — Catherine Tuttle(57) **CLAIM**

The ornamental design for a transparent liquid filled ball having three isolated interior compartments, as shown and described.

DESCRIPTION

FIG. 1 is a perspective view showing my new design for a transparent liquid filled ball having three isolated interior compartments;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view similar to FIG. 1 but showing the interior particles in a suspended state within the liquid.
